ARTHUR THOMAS WAKEFIELD, OF BALTIMORE, MARYLAND, ASSIGNOR TO THE
AMERICAN OIL COMPANY, OF BALTIMORE, MARYLAND

SEALED VALVE MECHANISM FOR LIQUID-DISPENSING SYSTEMS

Application filed October 22, 1927. Serial No. 228,053.

This application is a continuation in part of my copending application for liquid measuring systems, Serial No. 157,855, filed December 29, 1926.

5 The invention forming the subject matter of the present application relates broadly to the dispensing of liquid fuels, such as gasoline, etc., from filling stations; and, is designed primarily to effect accurate and 10 speedy measurement and dispensing of liquids from underground storage tanks.

In the fuel dispensing systems in common use at present, the piping and valve mechanism leading to the underground 15 storage tanks is usually embedded in the earth between the tank and the ground level. When the pumping mechanism below ground gets out of order, it is then necessary to dig up the ground around the tank 20 filling pipe in order to remove or repair the defective parts; otherwise a large manhole must be provided from the tank to the ground level around the filling pipe and a large manhole cover used to cover the 25 surface opening of the manhole.

It is one of the main objects of the present invention to construct the said pipe and the valve mechanism contained therein, so that all the mechanism may be easily removed 30 from the said pipe without breaking the pipe-embedding ground, or the pipe, when it becomes necessary to effect repairs in the dispensing mechanism.

As this invention is primarily designed 35 for use in systems dispensing very high grade and widely imitated liquid fuels, the invention also comprises a filler and closure cap of special construction and embodying a sealing valve having parts adapted to be 40 sealed to prevent unauthorized filling of the tank or tampering with the said valve mechanism.

Another object of the invention resides in the making of the several valves and other 45 removable parts in the pipe of progressively increasing sizes from bottom to top of the filling pipe, so that the lower positioned parts may pass readily and freely through the apertures seating the upper valves, etc.

50 Another and most important object of the

invention resides in the means for removing the removable parts from the filling pipe, whereby a single key may be used to seat and lock or remove all valves and other removable parts from any position on the 55 filling pipe.

Other objects of the invention will become apparent as the detailed description thereof proceeds.

In the drawings:—

Figure 1 is a central vertical section taken lengthwise through the foot valve mechanism and pipe connected to an underground storage tank;

Figure 2 is a fragmentary vertical section of the closure cap shown in Figure 1, but with a part thereof removed, and showing a specially constructed key wrench adapted to engage and remove all removable parts secured in said pipe;

Figure 3 is a fragmentary vertical section of the closure cap, but showing the closure and a sealing plug removed and showing the said key wrench in the process of removing a vacuum plug through the 75 sealing valve;

Figure 4 is an elevation of the said key wrench;

Figure 5 is a horizontal section on the line 5—5 of Figure 2;

Figure 6 is a plan of the sealing valve showing the parts thereof assembled but not interlocked;

Figure 7 is an elevation of the parts of the sealing valve assembled as shown in 85 Figure 6;

Figure 8 is an elevation of the said sealing valve, having the parts thereof relatively moved to interlocked position;

Figure 9 is an exploded elevation showing the parts of the sealing valve separated and ready to be assembled; and

Figure 10 is a top plan of the vacuum plug, illustrating the means to co-operate with the key wrench for removal of all plugs 95 of this type.

As shown in Figure 1, the underground storage tank 1 has a dispensing pipe 2 extending thereto, and secured thereto by any suitable co-operating fittings 3 and 4 103

secured to the pipe and tank respectively. The pipe 2 extends vertically upward from the tank 1; and at any suitable distance below the ground level h , has its upper end screwthreaded into the flanges of a T-fitting 6.

The fitting 6 has an internally screwthreaded arm projecting substantially horizontally to engage a pipe 8 extending a suitable distance laterally of fitting 6 to be connected to a downwardly extending pipe from the measuring pump (not shown). An internally screwthreaded flange 9 at the top of fitting 6 serves as a seat for the externally screwthreaded end 10 of a pipe 11 which has its upper end also externally screwthreaded to the correspondingly threaded lower end 12 of a closure and seal valve casing 13 having the top thereof ordinarily arranged flush with the ground level L.

In my prior application, Serial No. 157,855, I have shown the check valve mechanism as arranged at the foot of the discharge pipe and wholly within the tank. In the present case, I have arranged the check valve mechanism in the discharge pipe and outside the tank. In order to obviate chatter in the discharge operation, it is frequently advisable to use two or more of such valves in series, and I have designed the valve mechanism, in this instance, so that any desired number of valves may be attached to each other in series, and the whole series inserted or removed bodily from the discharge pipe.

The most convenient location for arranging these check valves lies in the T-fitting 6 at its point of connection with the lateral projection 7 where the said fitting is provided with an internally screwthreaded part 14. A cylindrical plug 15 has an externally screwthreaded flange 16 adapted to engage and seat in the said part 14. The plug 15 is provided with a beveled seat for 17 for the correspondingly beveled periphery 18 of the head 19 of a poppet valve 20. A bridge 21 extends transversely of the plug 15 and is provided with a central aperture 22 in which the stem 23 of valve 20 is guided. A nut 24 threaded on to the end of stem 23, and secured thereon by a cotter pin 25, prevents accidental removal of valve 20 from the valve plug 15.

The upper end of the valve plug 15 is provided with a pair of T-shaped segmental projections 26 arranged diametrically opposite each other. Each of said projections comprises a vertical part 27 having a pair of arms 28 and 29 extending from opposite sides of the top thereof, and lugs 30 depend from the outer end of each arm, to form recesses 31 adapted to receive either of the pins 32 on the rod 33 of a key wrench of peculiar construction.

The key wrench (see Figure 4) comprises the rod 33 having one end provided with a

cross head 34 to facilitate turning thereof, and having a cylinder 35 screwthreaded on to its lower end and fixed thereto by set screws 36. Below the end of rod 33, the cylinder is shaped to provide a flange 37 adapted to receive slidably the stem 38 of a machine screw 39, which is screwed into one end of a plunger 40. The plunger 40 fits snugly and slidably in the cylindrical recess 41, and the head 42 of screw 39 engages the flange 37 to limit the movement of plunger 40 outwardly of its recess 41, coil spring 43 surrounding the screw 39 and abutting at opposite ends against flange 37 and top of plunger 40, serves to hold the plunger 40 yielding projected from the cylinder.

The cylinder 35 of the key wrench fits snugly and rotatably between the diametrically opposed arcuate arms 28 and 29 and the plunger 40 thereof is normally projected far enough from its cylinder to force the pins 32 into seating engagement in recesses 31 when the wrench is positioned to effect this engagement and the end of the plunger 40 engages the head 19 of valve 20.

The slots 30' formed by separating the adjacent ends of arms 28 and 29, are adapted to permit entry of the pins 32 between the ends of lug three. In order to effect interlocking engagement of pins 32 with recesses 31, the cylinder 35 is inserted between the opposed arms 28 and 29 with the pins 32 in the slots 30' between ends of arms 28 and 29, downward pressure is applied to the rod 33 to force the cylinder 35 toward the head of valve 20, against the resistance of spring 43, until the pins 32 are below the lowest ends of lugs 30. The wrench is then turned in either direction until the opposite pins 32 strike the edges of the parts 26. The downward pressure on rod 33 is then released, and the spring 43 acting on plunger 40 forces the pins 32 upwardly into the diagonally opposite recesses 31. The cross head 34 may then be turned to effect either insertion or removal of plug 15 in or from its seat in the fitting 6.

The lower end of valve plug 15 is internally screwthreaded to receive the external screwthreads on a flange 44 formed on the upper end of a cylindrical valve casing 45. The said upper end is bevelled to form a seat for a poppet valve 46 similar in every respect to the valve 20 and similarly guided and limited as to reciprocate movement by the centrally apertured bridge 47 and nut 48. The lower end of valve casing 45 is also internally screwthreaded, and is adapted to receive a valve casing and mechanism similar in every respect to that last described. The upper valve plug alone has the wrench engaging lugs; all the other valve casings and mechanisms which may be connected to each other and suspended

from said plug are identical in every respect.

The vacuum plug 49 is screwthreaded into fitting 6 at the point where the upper end of connection 7 enters fitting 6, in order to prevent inaccuracies in measurement caused by variation in the pressures exerted by gases trapped in pipe 11 above the connection between the pump line 8 and fitting 6. The top of this plug is also provided with lugs 50 and 51 similar in every respect to the wrench receiving lugs 26 on the top of valve plug 15, and are adapted to be similarly engaged to effect removal or insertion of plug 49 from or in its position in fitting 6.

The closure casing 13 at the ground level is provided with an annular flange 52 spaced slightly from the top of the casing and forming a recess 53 to receive the closure plate 54. The flange 52 is provided with diametrically opposite slots 55 and 56 adapted to permit the passage of the locking bar 57 therethrough to the underside of flange 52. The bar 57 is screwthreaded onto a correspondingly screwthreaded rod 58 depending integrally from the bottom of plate 54 and a lock nut 59 on said rod 58 locks the bar 57 in proper position on rod 58 to ensure the plate 54 being drawn down firmly on to its seat when the said plate and bar are rotated to make the bar engage the underside of said flange 52.

The top of plate 54 is provided at its center with a square recess 60 having one side 61 thereof slightly undercut to receive the projection 62 formed on one side of the rectangular end 63 of plunger 40 which is held against rotation by the inner end 64 of one of the screw pins 32 slidably engaging a slot 65 formed lengthwise in said plunger. The operation of this squared end in locking the closure plate 54 on its seat 53 or removing it therefrom will be obvious from inspection of the drawing. The projection 62 engaging recess 61 enables the operator to lift the plate 54 by the end of plunger 63 without having to bend over and remove it by hand.

Immediately below the flange 52, the casing 13 is provided with one element 66 of a sealing valve which is secured to said casing 13 by a dowel pin 67. The element 66 is recessed to form a seat for the sealing plug 68, and said element 66 and plug 68 are provided with apertured projections 69 and 70 adapted to be relatively rotated until the apertures 71 and 72 register, in which position a wire 73 may be passed through the registering apertures and the ends thereof secured together as by a seal 74 of any usual type.

The plug 68 is provided centrally with a squared recess 75, similar in every respect to the recess 60 in the closure cap 54, adapted to receive the squared end 63 of the

key wrench to effect removal of said plug from its seat and rotation thereof on said seat when it is found necessary or desirable to lock the plug on its seat.

The element 66 is also provided with a pair of diametrically opposite L-slots 76 adapted to receive pins 77 and 78 suitably secured to or formed on plug 68, and to lock the said element and plug against axial separation.

In order to permit ready removal of the mechanism from the discharge pipe, the several valve and plug seats are made of such size as to permit the passage therethrough of every removable element below it. Thus the plug 49 is larger in diameter than plug 15, plug 68 is larger than plug 49, and the closure plate 54 is large enough to permit the removal of all the parts below it.

In this system the filling pipe for the storage tank is arranged near the end thereof remote from the discharge pipe 2, and is provided with a sealing closure mechanism similar to that at top of the discharge pipe 11. These two seals therefore prevent unauthorized filling or removal of contents from the storage tank, and operate as an effective check to ensure that nothing but the proper contents are stored in and dispensed from the system.

Having thus described my invention, what I claim is:—

1. A key for interlocking engagement with pipe plugs of the type described and comprising a rod having a cylinder at one end thereof, a piston slidable in said cylinder and having part normally projecting therefrom, and yielding means for holding said part projected.

2. A key for interlocking engagement with pipe plugs of the type described and comprising a rod having a cross bar at one end thereof and a cylinder at the other end, a piston slidable in said cylinder, yielding means in said cylinder holding said piston with a part normally projected from said cylinder, said part having the end thereof of polygonal cross section.

3. In a liquid discharge, the combination of a pipe for connection to a tank, having a side opening intermediate its ends; a valved plug having a seat in the pipe on one side of the side opening and having a pair of opposed T shaped wings with lugs extending from their tips to provide notches behind the lugs; and a solid plug, having a larger seat than the first, seated in the pipe on the other side of the side opening, having a similar pair of wings, so that both plugs may be grasped by a suitable key for inserting or removing, the first named passing through the seat of the second.

4. In a liquid discharge, the combination of a pipe for connection to a tank, having a side opening intermediate its ends; a valved

plug having a seat in the pipe on one side of the side opening and having a pair of opposed T shaped wings with lugs extending from their tips to provide notches behind the lugs, the wings forming a circular configuration on the plugs; a solid plug, having a larger seat than the first, seated in the pipe on the other side of the side opening, having a similar pair of wings; and a key comprising a stem bearing a cylinder adapted to enter the circular configuration of the wings, with pins adapted to enter said notches and a plunger partly projected from the cylinder by a spring for holding the pins in the notches.

5. The same structure as claim 3; a closure for the end of the pipe nearest the solid plug, having a polygonal socket in its face; and a key having a polygonal end and 20 side pins for engaging the closure and the two plugs.

In testimony whereof I affix my signature.
ARTHUR THOMAS WAKEFIELD.
